INVENTOR

Brice W. McDowell,

BY
J. R. Little, Esq.
ATTORNEY.

UNITED STATES PATENT OFFICE.

BRICE W. McDOWELL, OF NEW YORK, N. Y.

RAILWAY-SIGNAL.

SPECIFICATION forming part of Letters Patent No. 693,883, dated February 25, 1902.

Application filed March 23, 1901. Serial No. 52,648. (No model.)

To all whom it may concern:

Be it known that I, BRICE W. McDOWELL, a subject of the King of Great Britain, residing at New York, in the county and State of New York, have invented certain new and useful Improvements in Railway-Signals, of which the following is a specification.

This invention relates to railway-signals; and it has for its object to provide an improved mechanism of this class of the semaphore type in which the semaphore-arm shall carry the lighting means and shall carry means for automatically changing the color of the light emitted thereby in the movement of the semaphore-arm.

My invention has for its object, further, to provide an improved semaphore-signal mechanism which is superior in point of ease and positiveness of operation and general efficiency.

In the drawings, Figure 1 is a perspective view illustrating my improved railway-signal mechanism in operative position at one side of a railway road-bed; the semaphore being shown in full lines in inoperative position and in dotted lines in operative position. Fig. 2 is a detail transverse sectional view of the semaphore, taken upon the line *x x*, Fig. 3. Fig. 3 is a detail longitudinal sectional view of the semaphore. Fig. 4 is a detail vertical sectional view of the semaphore-support, taken upon the line *y y*, Fig. 3. Fig. 5 is a detail sectional view taken through the semaphore-shaft and looking forwardly.

Corresponding parts in all the figures are denoted by the same reference characters.

Referring to the drawings, 1 designates my improved railway-signal, which is provided with the customary semaphore-arm 2 and semaphore-support 3. The semaphore carries lighting means 4, and means 5 for automatically altering the character of the light emitted by the same in the movement of the semaphore-arm.

6 designates means for operating the semaphore-arm, which in the construction illustrated comprises a hand-lever 7 and operative connections 8 between the same and the semaphore-arm.

The semaphore-arm 2 is eccentrically carried upon the semaphore-shaft 9, which is

journaled in the upper end portion of the semaphore-support 3.

It will be understood that the semaphore may be operated by any of the well-known means, either by the wheels of the locomotive or car or by actuation from a signal-tower or otherwise.

In the preferred form of construction the semaphore-arm 2 is chambered transversely at each end, as at 10, to receive the lighting means 4, which means consist of incandescent electric bulbs or lamps 11. The end portions of the chambers 10 are closed by plates 12, of glass or other suitable translucent or transparent material, which may be of any preferred color, but are preferably white, so that the light normally emitted by the incandescent bulbs 11 is a pure white light. The chambers 10 are provided at each end or beneath each face of the semaphore-arm 2 with a broad lateral extension 13, opposite which is formed a narrow lateral extension 14. The means 5 for automatically altering the character of the light emitted by the bulbs 11 are housed normally within the broad extensions 13 of the chambers 10, and consist of circular glass disks or plates 15, which are free to move across the end portions of the chambers 10. The movement of the glass disks 15 into operative position is limited by the narrow extensions of the chamber 10, in which extensions the edge portions of the advancing disks are received. The disks 15 are preferably colored red, but may be of any color, as predetermined by the system of signaling to which the use of my improved signal is adapted. The lateral extensions 13 and 14 of the chambers 10 are preferably formed flush with the faces of the semaphore-arm, and said extensions, as well as the chambers 10, may be closed by detachable plates 16, which also may carry the fixed white glasses 12. The circular disks 15 of colored glass are free to traverse the extensions 13 and 14, and thus move across and close the end portions of the chambers 10. The disks 15 are moved into and out of operative position by the tilting movement of the semaphore-arm, which tilting movement is effected by actuation of the operating means 6. When the semaphore-arm is moved into horizontal

position, the colored-glass disks 15 roll freely, because of their circular formation, out of the broad extensions 13 of the chambers 10 and effectively close the end portions of the 5 chamber 10 against the passage of all light other than that which passes through themselves. The movement of the closed disks 15 into operative position is facilitated by the form of the extensions 13 of the chambers 10, 10 which extensions are provided with curved walls 17. The colored-glass disks 15 are preferably of slightly greater diameter than the chambers 10 to insure effective closure of the chambers 10 against the passage of light 15 around said disks 15, and the end portions of the chambers 10, between the lateral extensions 13 and 14, are preferably of enlarged diameter, as at 18, to accommodate the disks 15. The extensions 13 and 14, of the chambers 10 20 are of the same diameter as the enlarged end portions 18 of said chambers.

The semaphore-arm 2 may be chambered at the top, as at 19, to receive the line-wires 20 for the electric bulbs 11, and said chamber 19 25 may be provided with a detachable cover or closure 21, whereby access to the line-wires may be facilitated. The electric bulbs 11 may be connected in series or in multiple, as preferred.

30 The semaphore-support 3 preferably consists of a vertical casing 22, in the upper end portion of which the semaphore-shaft 9 is journaled, and the operative connections 8 may consist of a vertical shaft 23, which is 35 journaled in the casing 22, and a horizontal shaft 24, which is journaled in the lower end portion of the casing 22 and projects exteriorly of the same. The hand-lever 7 is fixed to the horizontal shaft 24. The semaphore-shaft 9 40 is operatively connected with the vertical shaft 23 by means of beveled gears 25, and the vertical shaft 23 is operatively connected with the horizontal shaft 24 by means of beveled gears 26. The semaphore-shaft 9 45 is provided within the casing 22 with a stop device 27, which limits the pivotal movement of the semaphore-arm 2, whereby the semaphore-arm may be actuated by the operating means 6 into either exactly vertical or exactly horizontal position. In the preferred form of 50 construction the stop device 27 consists of a disk 28, which is secured to the semaphore-shaft 9 and is cut away through a predetermined portion of its periphery, as at 29, to form shoulders 30, which coact with stops 31, arranged within the casing 22. The line-wires 20 may enter the casing 22 at the bottom of the same, as at 31, and extend vertically through the same to the top portion, where they may exit 55 through a suitable opening, as at 33, at a point adjacent the chamber 19, through which they pass to the electric bulbs 11.

The line-wires 20 may be supplied with current by a suitable battery 34 or other source 60 of electrical energy, and the electrical circuit through the line-wires and the electric bulbs may be controlled by suitable switches 35.

The operation and advantages of my improved railway-signal will be readily understood by those skilled in the art to which it 70 appertains. The signal is adapted for use in connection with railway-switches, railway block systems, and for a variety of similar purposes. The semaphore-arm 2 normally occupies a vertical position, or a position in 75 which it extends substantially in parallelism with the semaphore-support 3. With the semaphore-arm in this position and a closed circuit having been established through the line-wires 20, a white light will be displayed 80 by the semaphore-arm and convey to the engineer or trainmen on an approaching train the required intelligence as to the condition of the road ahead. With the semaphore-arm in this position the colored disks 15 occupy 85 positions within the broad extensions 13 of the chambers 10, which extensions 13 are so arranged with respect to the end portions of the chambers 10 that the disks 15 lie beneath 90 said end portions, with the semaphore in vertical position. When the semaphore-arm is turned by the operating means 6 into horizontal position, the colored-glass disks 15 roll out of the broad extensions 13 of the chambers 10 into position to close the enlarged end 95 portions 18 of the chambers 10 and are maintained in said position by entering the narrow extensions 14 of the chambers 10. The light emitted by the bulbs 11 is now transformed from white to red in color and conveys 100 the required intelligence to the engineer or trainmen of the approaching train.

The movement of the semaphore-arm is effected by manipulation of the hand-lever 7; but it is understood that the operating means 105 6 may be varied to meet the conditions of use or preference, according to the nature of the signaling system in which my improved signal is employed. The casing 22, which constitutes the semaphore-support 3, effectively houses the major portion of the operating means for the semaphore-arm, as well as the stop device 27 and the line-wires 20.

The semaphore-arm 2 is simple in construction, and access may at all times be had to the 115 disks 15 and incandescent bulbs 11 by detaching the closure-plate 16.

The entire device is simple in construction, positive and unfailing in operation, and it is adapted to all forms of railway and allied signaling.

I do not desire to be understood as limiting myself to the details of construction and arrangement as herein described and illustrated, as it is manifest that variations and modifications may be made in the features of construction and arrangement in the adaptation of the device to various conditions of use without departing from the spirit and scope of my invention and improvements. I therefore reserve the right to all such variation and modification as properly falls within the scope of my invention and the terms of the following claims.

Having thus described my invention, I claim and desire to secure by Letters Patent—

1. An improved signal of the class described, comprising a pivoted semaphore, lighting means carried by the same, and a translucent disk slidably carried by the semaphore and arranged to be moved in the movement of the semaphore into the path of light emitted by the lighting means.
- 5 2. An improved signal of the class described, comprising a pivoted semaphore, lighting means carried by said semaphore at each end of the same, and two translucent disks slidably carried by the semaphore and arranged to be moved respectively in the movement of the semaphore into the paths of light emitted by the lighting means at each end of said semaphore.
- 10 3. An improved signal of the class described, comprising a pivoted semaphore, lighting means carried by the same, and two translucent disks carried by the semaphore

at either side of the lighting means and arranged to be moved in the movement of the semaphore into the path of light emitted by the lighting means.

4. An improved signal of the class described, comprising a movable semaphore, separate lighting means carried by said semaphore at each end of the same, means for jointly energizing said lighting means, and translucent disks slidably carried by the semaphore with respect to both of said lighting means and arranged to be moved in the movement of the semaphore into the paths of light emitted by the said lighting means to "set" the signal.

In testimony whereof I have signed my name in the presence of two subscribing witnesses.

BRICE W. McDOWELL.
